UNITED STATES PATENT OFFICE

GARTH G. GILPIN, OF RIVERSIDE, ILLINOIS, ASSIGNOR TO UNION METAL PRODUCTS COMPANY, OF CHICAGO, ILLINOIS, A CORPORATION OF DELAWARE

CAST METAL END PLATE

Application filed November 6, 1929. Serial No. 405,133.

My invention relates to the construction of railway cars and more particularly to the "end plate" thereof. The end plate of a railway freight car is the upper horizontal structural member spanning the distance between the opposite corner posts and opposite side plates and usually formed so as to support the roof.

The object of the invention is to provide a single piece cast metal end plate formed with integral means for attachment to the side plates and to the corner posts and also preferably the end wall and roof of the car and to so form such member as to provide a waterproof connection between the side plates and corner posts and also between the roof and end wall of the car.

Another object is to form such cast metal end plate so that it can be readily detached and removed from the other elements of the car.

Another object is to form the component parts of the end plate of a single piece cast member so as to eliminate the possibility of loose connections which would permit relative motion between the component parts of the end plate and between the adjacent frame members of the car which would be caused by the vibration of the car in motion due to rough and uneven track and steel wheels rolling on steel rails. The amount of motion in a car in service has been increased very much recently by the higher speeds and longer trains of present day railroading.

Another object is to eliminate the cost and delay in fabricating and assembling the numerous component parts of the present structural steel end plate.

By nature of their requirements railway freight train cars are out of doors substantially all of the time, therefore, are subjected to corrosive action of the elements, and while paint and other non-corrosive coatings have been applied to the car parts, such protection is not only expensive in time and money, but does not remain on such car parts. Cast metal, particularly cast steel, has more than twice the resistance to corrosion than rolled steel, therefore, one of the objects of the invention is to make the end plate of cast metal, pref-

erably cast steel, to enable it to resist corrosion. Furthermore, to provide a construction wherein the metal can be disposed and positioned to accommodate the stresses set up by the car in service. Such a cast construction necessitates a minimum amount of material for strength requirements.

In the drawings:

Fig. 1 shows a fragmentary elevation of a part of a railway car provided with the cast metal end plate.

Fig. 2 is a plan view of Fig. 1.

Fig. 3 is a partial side elevation of Fig. 1.

Figs. 4, 5 and 6 show a modified construction.

Figs. 7, 8 and 9 show another modified construction.

In the forms illustrated I have shown oppositely disposed side plates 2 of Z-shape formation and oppositely disposed corner posts 3 of Z-shape formation adjacent the ends of the respective side plates. The end plate consists of a single piece cast metal comprising a Z-shape portion consisting of a web 4; an upper flange 5 and a lower flange 6, which portion extends between the opposite side plates 2 and also between the opposite corner posts 3 and is formed at each end with a lateral extension 7, which is also preferably Z-shaped and which is secured to the adjacent side plate and corner post. In order to form a rigid attachment and eliminate possibilities of a loose connection, I prefer to attach the web 4 of the end plate to the web 8 of the side plate and the flange 6 of the end plate to the flange 9 of the side plate.

The lateral extension 7 overlaps the end of the side plate 2 and the corner post 3 and provides a weatherproof construction.

The end plate flange 6 overlaps and is secured to the end wall 12 of the car. This flange also preferably is secured to the web and flange of the corner post 3 and is preferably extended further and secured to the depending flange of the side plate 2.

In the form shown in Figs. 1, 2 and 3 the roof 16 comprises a rigid metallic sheet which overlaps and is secured to the flange 5 of the

end plate and is also overlapped and secured to a flange of the side plate 2.

The roof shown in Figs. 4, 5 and 6 is supported by ridge pole 20 and purlins 21 which 5 rest upon a horizontal rib 22 formed integral with the flange 5 of the end plate, which rib merges into the flanges 23 of the extensions 7 and is preferably increased in width (24) toward said extensions to provide a gusset 10 effect. This rib stiffens the upper margin of the end plate flange against the tendency of the car to weave in service and also the tendency of the roof to shift by its inertia when the car stops.

15 I also prefer to provide brackets which stiffen the relation between the flange 5 and web 4 of the end plate and also may be altered to support the running board bracket 27.

In the form shown in Figs. 7, 8 and 9 the 20 end plate is provided with an outwardly extending flange 30 supporting the roof 31 to which it is secured. The flange conforms to the slope of the roof whether it be rounded, as shown, or apiced. Brackets 32-33 are 25 provided to support the longitudinal roof framing members when they are used. In this modification the upper flange 5 is provided with a gusset 34 which extends over the side plate 2 and merges into the extension 7. 30 The corner post is omitted and the end wall 12 is provided with a flange 35 which is secured to the member 36 which is an integral part of the end plate. The side wall 38 (shown as wood) is secured to the flange 35. 35 These figures, 7, 8 and 9, also show a load lifting beam 36 which preferably extends longitudinally of the car and is spaced apart from the roof sheets so that a chain, hook or other load lifting apparatus may be conveniently 40 attached to it. This beam is supported by the bracket 33 which is integral with the end plate. Numeral 39 shows the running board bracket.

The accompanying drawings illustrate the 45 preferred form of the invention, though it is to be understood that the invention is not limited to the exact details of construction shown and described, as it is obvious that various modifications thereof, within the 50 scope of the claims, will occur to persons skilled in the art.

I claim:

1. In a railway car, the combination of side plates, and a single piece cast metal member comprising a Z-shaped portion extending between said plates formed at each end with a Z-shaped lateral extension secured to the adjacent side plate.
2. In a railway car, the combination of 60 Z-shaped side plates, and a single piece cast metal member comprising a Z-shaped portion extending between said plates formed at each end with a Z-shaped lateral extension overlapping and secured to the adjacent side plate.

3. In a railway car, the combination of Z-shaped side plates, and a single piece cast metal member comprising a Z-shaped portion extending between said plates formed at each end with a Z-shaped lateral extension secured to the flanges of the adjacent side plate. 70

4. In a railway car, the combination of Z-shaped side plates, and a single piece cast metal member comprising a Z-shaped portion extending between said plates formed at each end with a Z-shaped lateral extension secured to the web and flanges of the adjacent side plate. 75

5. In a railway car, the combination of side plates, Z-shaped corner posts, and a single piece cast metal member comprising a Z-shaped portion extending between said plates and said corner posts formed at each end with a lateral extension secured to the adjacent side plate, said member also formed with a part at each end secured to the adjacent corner post. 80

6. In a railway car, the combination of side plates, corner posts, and a single piece cast metal member comprising a Z-shaped portion extending between said plates and said corner posts formed at each end with a lateral extension overlapping and secured to the adjacent side plate, said member also formed with a part at each end overlapping and secured to the adjacent corner post. 85

7. In a railway car, the combination of side plates, Z-shaped corner posts, and a single piece cast metal member comprising a Z-shaped portion extending between said plates and said corner posts formed at each end with a lateral extension secured to the adjacent side plate, said member also formed with a part at each end secured to the flanges of the adjacent corner post. 90

8. In a railway car, the combination of Z-shaped side plates, Z-shaped corner posts, and a single piece cast metal member comprising a Z-shaped portion extending between said plates and said corner posts formed at each end with a Z-shaped lateral extension secured to the web and flanges of the adjacent side plate, said member also formed with a part at each end secured to the web and flanges of the adjacent corner post. 100

9. In a railway car, the combination of side plates, a single piece cast metal member comprising a Z-shaped portion extending between said plates formed at each end with a lateral extension secured to the adjacent side plate, and a roof secured to said portion and said extensions. 110

10. In a railway car, the combination of side plates, and a single piece cast metal member comprising a Z-shaped portion extending between said plates formed at each end with a lateral extension secured to the adjacent side plate, said portion provided with an integral flange arranged to support 115

130

horizontal frame members of the roof of the car.

11. In a railway car, the combination of side plates, and a single piece cast metal member comprising a Z-shaped portion extending between said plates formed at each end with a lateral extension secured to the adjacent side plate, said portion provided with stiffening brackets, some of which are arranged for attachment of a running board bracket.

10 12. In a railway car, the combination of Z-shaped side plates, Z-shaped corner posts, a single piece cast metal member comprising a Z-shaped portion extending between said plates and said corner posts formed at each 15 end with a lateral extension secured to the adjacent side plate, and a roof secured to said portion and said extensions, said portion provided with an integral flange arranged to support horizontal frame members 20 of the roof of the car, some of which are arranged for attachment of a running board bracket.

13. In a railway car, the combination of 25 spaced apart side plates, spaced apart vertical posts adjacent one end of said side plates, and a single piece cast metal member spanning the distance between said side plates and said corner posts and overlying and secured to said side plates and corner posts.

30 14. In a railway car, the combination of spaced apart side plates, spaced apart vertical posts adjacent one end of said side plates, an end wall, and a single piece cast metal member spanning the distance between said side plates and said corner posts and overlying and secured to said side plates, corner posts and end wall.

35 15. A cast metal end plate for a railway 40 car formed with integral means for attachment of side plates, corner posts, end wall and roof of a railway car.
